WALL PLAQUE

John A. Boroszewski, 155 E. Grand Blvd.,
Cheektowaga, N.Y. 14225

Filed Apr. 9, 1971, Ser. No. 132,936

Term of patent 14 years

Int. Cl. D11—03

U.S. Cl. D29—23

FIG. 1 is a plan view of the wall plaque embodying my new design, details within the segment being repeated throughout the periphery thereof;

FIG. 2 is a side elevational view taken from the right of FIG. 1; and

FIG. 3 is a cross sectional view taken along line 3—3 of FIG. 1.

I claim:

The ornamental design for a wall plaque, substantially as shown and described.
